(57) **CLAIM**

The ornamental design for a packaging container, as shown and described.

DESCRIPTION

FIG. 1 is a front view of a packaging container showing our new design;

FIG. 2 is a rear view thereof;

FIG. 3 is a right side view thereof; the left side view is a mirror image of the right side view;

FIG. 4 is a top plan view thereof;

FIG. 5 is a bottom plan view thereof;

FIG. 6 is a perspective view thereof;

FIG. 7 is an enlarged fragmentary view thereof, taken along line 7-7 shown in FIG. 1;

FIG. 8 is a cross-sectional view taken along line 8-8 shown in FIG. 4; and,

FIG. 9 is a perspective view thereof showing the packaging container in use.

In the drawings, the broken lines show portions of a packaging container that form no part of the claim.
